UNITED STATES PATENT OFFICE.

WILLIAM JHON SANDERSON, OF BIRMINGHAM, ALABAMA, ASSIGNOR OF ONE-THIRD TO AUGUST L. H. HINRICHSEN AND ONE-THIRD TO CHARLES W. HADCOCK, OF BIRMINGHAM, ALABAMA.

ADJUSTABLE TAPER-BORING DEVICE.

1,046,496.

Specification of Letters Patent. Patented Dec. 10, 1912.

Application filed November 11, 1911. Serial No. 659,798.

To all whom it may concern:

Be it known that I, WILLIAM J. SANDERSON, a citizen of the United States, residing at Birmingham, in the county of Jefferson 5 and State of Alabama, have invented certain new and useful Improvements in Adjustable Taper-Boring Devices, of which the following is a specification.

The present invention relates to a boring 10 device adapted to be employed in forming cylindrical openings or for cutting tapered bores of different shapes.

An important object of my invention is to provide means of the above mentioned 15 character which may be readily adjusted for cutting different shapes of tapered bores.

A further object of this invention is to provide an adjustable taper boring device having novel means to effect the longitudinal 20 travel of the tool or cutter.

A further object of the invention is to provide a device of the above mentioned character, which is simple in construction, cheap to manufacture, and easy to operate.

25 Other objects and advantages of the invention will be apparent during the course of the following description.

In the accompanying drawings forming a part of this specification and in which like 30 numerals are employed to designate like parts throughout the same, Figure 1 is a side elevation of the device, showing it applied to parts of a drill press, Fig. 2 is an edge view of the same, Fig. 3 is an enlarged 35 longitudinal sectional view, taken through the movable carriage and relatively stationary track, associated elements being shown in elevation, Fig. 4 is a horizontal sectional view taken on line 4-4 of Fig. 1, Fig. 5 is a similar view taken on line 5-5 of Fig. 1, 40 Fig. 6 is a similar view taken on line 6-6 of Fig. 1, and, Fig. 7 is a similar view taken on line 7-7 of Fig. 1.

In the drawings wherein is illustrated a 45 preferred embodiment of my invention, the numeral 1 designates the upper frame of a drill press, upon which is mounted a bearing 2, for receiving a rotatable shaft 3. This shaft is provided at its lower end with a 50 socket 4, preferably square in cross-section, for receiving the upper end of a spindle 5. The lower end of this spindle is journaled in a fixed bearing 6. Although I have shown my device as applied to a drill press,

I do not wish to restrict myself to such practice alone, as the same can be advantageously used in connection with a lathe, boring mill, radial drill, or any machine or appliance having a revolving element.

The numeral 7 (see Figs. 1 and 3) designates a relatively stationary track, which is substantially trapezoidal in horizontal cross-section, as shown. This track is provided upon one side thereof with curved arms or segments 8, rigidly connected therewith and disposed upon opposite sides of the spindle or rotatable element 5, as more clearly shown in Fig. 6. These curved arms 8 are provided with longitudinal slots 9, for receiving a bolt 10 carried by the spindle 5. 70 This bolt carries a nut 11, for rigidly clamping the arms 8 to the spindle 5 in adjustment at different positions with relation to said spindle. One of the arms 8 is provided upon its outer surface with a scale 12, coöperating with a pointer 13, which is fixedly secured to the spindle 5.

Pivotedly mounted upon the spindle 5 below the track 7 is a substantially U-shaped tool-holder guide or rest 14, more clearly shown in Figs. 1 and 7. This tool-holder guide is pivotally connected with the spindle 5 by a bolt 15, as shown. The guide 14 is provided through its upper portions with curved slots 16, for receiving the ends of a 85 clamping bolt 17, carried by the spindle 5, as shown. The guide 14 is provided with a longitudinal slot or recess 18 for receiving the lower portion of a longitudinally movable tool-holder 19. This tool-holder 19 is 90 provided at its lower end with a transverse opening for receiving a tool or cutter 20, held in place by a clamping bolt 21, as shown. The intermediate portion of the tool-holder 19 slidably engages the lower portion of the 95 track 7 and the upper portion of said tool-holder is off-set, as shown. The upper off-set portion of the tool-holder 19 is rigidly connected with a carriage 7' by clamps 22, held in place by bolts 23 engaging the carriage, as shown.

The carriage 7' is approximately U-shaped in horizontal cross-section, affording an opening 24, for receiving a feed screw 25 and the track 7. Interposed between the track 105 7 and carriage 7' is a gib or strip 7^a held in place by adjusting screws 7^b. The lower end of this feed screw operates within a screw-

threaded opening 26 formed through the upper end of the track 7. Disposed below the screw-threaded opening 26 is a counter-bore 27 formed through the track 7, as shown.

5 The upper end of the feed screw 25 is provided with a smooth extension 28, rotatably mounted in an opening 29 formed through the upper portion of the carriage 7'. The feed screw 25 is provided below and adjacent the extension 28 with an annular flange 30, as shown. The extension 28 continues in a reduced portion 31, upon which is mounted a feed drive or star wheel 32. This feed drive cannot turn on the portion 31

10 and when rotated will effect a rotation of the feed screw. Clamping nuts 33 are preferably carried by the reduced portion 31 above and below the feed drive 32. The feed drive comprises arms 34. Connected with

15 the frame 1 is a fixed feed drive arm 35, the lower end portion of which is disposed in the path of travel of the arm 34 of the feed drive. The arm 35 is preferably provided with a longitudinal slot 36 for receiving

20 clamping bolts 37 carried by the frame 1.

25 The operation of the device is as follows:—When the tool-holder 19 is in the vertical position, as shown in Fig. 1, the device may be employed to cut cylindrical bores. When it is desired to cut tapered bores, the nut 11 is unscrewed to permit of angular adjustment of the track 7 with respect to the spindle 5, the extent of the angle of inclination of the track being indicated

30 by the pointer 13 on the scale 12. The track 7 is now locked to the spindle by screwing up the nut 11. The guide 14 has previously been unclamped from the spindle 5 by proper manipulation of the clamping bolt 17, whereby said guide will be free to swing to occupy an angular position corresponding to that of the tool-holder 19. The guide 14 is now locked to the spindle 5 by proper manipulation of the clamping bolt 17. The

35 feed drive arm 35 has its lower portion disposed in the path of travel of the arms 34 of the feed drive and when the track 7 is angularly adjusted, as above described, a suitable feed drive arm 35' is provided so that

40 its lower portion will be disposed in the path of travel of said arms 34, as indicated in dotted lines in Fig. 1. As the spindle 5 revolves it carries all the elements of the device with it and the tool or cutter 20 will accordingly cut the desired bore. When the arms 34 engage the stationary arm 35 a step by step turning movement is imparted to the feed screw 25, causing the carriage 7' to travel longitudinally and also the tool holder 19.

I wish it understood that the form of my invention herewith shown and described is to be taken as a preferred example of the same and that certain changes in the shape, size, and arrangement of parts may be re-

sorted to without departing from the spirit of the invention as indicated by the scope of the subjoined claims.

Having thus described my invention, I claim:

1. The combination with a rotatable element, of a track, a segment connected therewith and provided with a scale, clamping means carried by the rotatable element to engage said segment, a pointer carried by the rotatable element to coöperate with said scale, a carriage movably mounted on the track, a tool holder connected with the carriage, a tool holder guide angularly adjustably connected with the rotatable element to engage the lower portion of the tool holder, and means to move the carriage longitudinally during the rotation of said rotatable element.

2. The combination with a rotatable element, of a track adapted to be disposed at different angular positions with relation to said rotatable element, an arm connected with said track and provided with a curved longitudinal slot, a clamping element carried by said rotatable element and disposed in the longitudinal slot, a tool holder, a carriage longitudinally movably mounted on the track and connected with the tool holder, and means to effect the longitudinal travel of said carriage including a feed screw and star-wheel.

3. The combination with a rotatable element, of a track adapted to be disposed at different angular positions with relation to the rotatable element, suitable connecting means between the track and rotatable element whereby the former may be so angularly adjusted, a carriage longitudinally movably mounted upon the track, a feed screw extending longitudinally of the track and carriage to effect the travel of said carriage, a star-wheel mounted upon the free end portion of the feed screw and adapted to be bodily moved with such feed screw when the carriage and track are moved to a desired angular position, and an element disposed in the path of travel of the star-wheel.

4. The combination with a rotatable element, of a track adapted to be disposed at different angular positions with relation to the rotatable element, adjustable means connecting said track and rotatable element, a carriage movably mounted on the track, means to move the carriage, a tool-holder connected with the carriage, and an angularly adjustable guide element connected with the rotatable element and engaging the tool holder.

5. The combination with a rotatable element, of a track, a segment provided with a scale and connected therewith, a clamping device carried by the rotatable element and engaging the segment, a carriage mounted

on the track, means to move the carriage longitudinally, and a tool-holder connected with the carriage.

6. The combination with a rotatable element, of a track adapted to be bodily moved with relation to the rotatable element for assuming different angular positions with relation thereto, suitable connecting means between the track and rotatable element, said track being provided with a screw-threaded axial opening, a carriage mounted upon the track to travel longitudinally thereof, a feed screw connected with the carriage so that said feed screw is free to turn

and is prevented from having any perceptible longitudinal movement with relation thereto, said feed screw having its lower end disposed within the screw-threaded axial opening of the track, a star-wheel connected with the upper portion of the feed screw, and an element disposed in the path of travel of the star-wheel.

In testimony whereof I affix my signature in presence of two witnesses.

WILLIAM JHON SANDERSON.
